UNITED STATES PATENT OFFICE

JAMES L. BALDWIN, OF CHICAGO, ILLINOIS

CASH CARRIER

Application filed August 6, 1930. Serial No. 473,434.

My invention relates to cash carriers of the types used in department stores and like establishments, and more particularly to the single flight variety of carrier illustrated in 5 my Patent Number 745,951, dated December 1, 1903, and my main object is to provide an improved apparatus in which rigidity and alinement are the chief factors.

A further object of the invention is to include in the novel apparatus means for the self-adjustment of the mechanism between the sending and receiving stations in order to relieve strain and ease the operation of the apparatus.

15 A still further object of the invention is to design the apparatus at the sending station on lines of simplicity and compactness.

Another object of the invention is to provide novel bearing means for the shock absorbing element at the receiving station, whereby to relieve the support of the apparatus at such station from interference, vibration and noise.

A final but nevertheless important object 25 of the invention is to construct the novel apparatus with units of a rugged nature, whereby to render the apparatus durable and free from trouble for long periods.

With the above objects in view and any 30 others that may suggest themselves from the specification and claims to follow, a better understanding of the invention may be had by reference to the accompanying drawings in which—

35 Fig. 1 is an elevation of the apparatus at the sending station, partly broken away, to save space;

Fig. 2 is a section on the line 2—2 of Fig. 1;

40 Fig. 3 is an elevation of a connecting strap used in Figure 1;

Figs. 4, 5, and 6, are respectively, sections on the lines 4—4, 5—5 and 6—6 of Figure 1;

Fig. 7 is an elevation of the apparatus at the receiving station;

45 Fig. 8 is a plan view of a guide shown in Figure 7; and

Fig. 9 is an end view of the said guide from the right, partly in section.

The sending station is usually over a clerk's counter, and may involve a suitable support

15, as shown in Figure 1 of the drawings. This support may be in the nature of a socket to receive a plug 16 forming the origin of a downward bracket 17, the plug being secured in the socket by a set screw 18. The bracket 17 also receives proper bracing means between it and a lower support 15a, such bracing means mainly comprising metal straps 19 pivoted at 20 to an ear extension 21 of a collar 22 which is slidably mounted on the bracket 17. The straps 19 extend in divergent courses and are twisted to terminate and lie flatly under the support extension 15a, being there secured by screws 19a as clearly shown in Fig. 1. The 65 bracket 17 is thus secured at three points and firmly holds its position.

In general, the mechanism of the sending unit is similar to that covered in the above mentioned patent comprising a base fixture 23, a bracing arm 24 in connection therewith, a bumper bracket 25, and a cable-retaining cross head 26. I have also shown a bumper recoil element 26a, and a ratchet track wire 70 tightener 26b used in late types of sending 75 units. In the novel apparatus I have created a more rigid relation between the moving parts and the stationary ones by altering the design and connection of the bracing arm 24 as shown in Fig. 2. It is now seen that the 80 bracing arm 24 is of square cross section, but it is understood that I may construct the same of polygonal or other angular cross section without departing from the spirit of the improvement. Consequently, the bearing 85 25a of the bumper bracket 25 and the bearing 27a of the terminal wheel hanger 27 are squarely bored to tightly receive the arm 24; and the bearing 26a of the cross head 26 and the bearing 23a of the fixture 23 are squarely 90 bored to slidably receive the arm.

As noted particularly in Fig. 6, the fixture 23 is vertically split into two halves. A bolt 23b secures these at the top, at the same time exerting a clamping influence upon the arm 24; and the rear assembly of the fixture components is clamped between the jaws 28 of a ring 29 freely mounted upon the supporting bracket 17 in a rotary sense. The jaws 28 are engageable with the fixture 23

by the operation of a bolt 30; and the ring 29 is fixed against vertical departure by being inserted between upper and lower sections of the collar 22, as clearly shown in Fig. 1. Some distance above the collar 22, the bracket 17 receives a ring clamp 31, whose jaws 31a receive between them the rear end of the bracing arm 24. Here the jaws and the arm are perforated to dispose a securing screw 32, the parts being so dimensioned that the advance of the screw will first tighten the clamp upon the bracket and then engage the jaws 31a with the arm 24.

It will be seen that the combination of the clamps 31 and 22 as related to the simple and continuous bracket 17 enables the mechanism to be mounted at any point along the bracket. Thus, if it is found that the mechanism can operate more efficiently near the upper portion of the bracket, the lower portion thereof may be cut off, saving material, making the installation compact and removing a part that would amount to an obstruction. Thus, brackets can be carried in different lengths to apply to individual situations. It is further apparent that the improved mechanism is readily adjustable to the direction of the track wire 33, since the bolts 30 and 32 can be loosened somewhat until the arm 24 and fixture 23 are at the right angle, and then tightened to fix the position of these parts. Further, the angular form of the arm 24 not only adds to the rigidity of the fixture 23, but also locks the bumper bracket 25 and the wheel hanger 27 from lateral departure or vibration due to the shock or strain suffered by the sending unit. The elements of the unit are therefore in vertical alinement at all times, eliminating looseness of the mechanisms and unsteadiness in the travel of the carrier.

Figs. 7 to 9 illustrate the remote or receiving unit of the apparatus. Here it is seen that the carrier and catch therefor are generally on the same lines as covered in the patent aforesaid. The bumper bar 34 and its accessory parts have, however, been improved. This bar is now made square or of other suitable angular cross section, and it is caused to enter a skeleton receptacle 35, the remote ends 35a of which is solid and bored to slidably receive the bar. The latter carries a long cushioning spring 36 for the impact of the carrier, this spring entering the receptacle 35 and lodging against the solid end 35a thereof; and beyond the receptacle the bar 34 receives a rebound spring 37. The receptacle 35 is extended beyond the end 35a with a semi-spherical cup 35b which is slotted at 35c. In the cup sets the rounded head 38a of a bolt 38, which passes through the slot 35c and the jaws 39 of a clamp 40. This clamp is applied to a horizontal rod 41 which may project from the cashier's booth or any

other fixture at the receiving station, the illustration of such a fixture not being deemed necessary. The receptacle 35 is extended on its upper side with a hook 42 upon which the loop 33a of the remote end of the track wire 33 is caught, the frontal flange 35c of the receptacle 35 being perforated as indicated at 35d to permit the passage of the track wire on its way to the hook 42. The receptacle also has a bottom duplicate 42a of the hook 42 and bottom and lateral perforations 35d in order that the track wire may still apply when the receptacle has been turned 90 or 180 degrees before applied to the bar 34. Where this action is to the extent of 180 degrees the track wire extends directly from the perforation to the hook 42a; however, where the turn is only through 90 degrees, it is necessary to swing the track wire laterally from the perforation in order to reach the selected hook 42 or 42a. The reason for duplicating the hook 42 on the opposite side of the receptacle is to permit a similar installation to be made in close proximity to the present one, that is, where another track wire and carrier are desired to lead closely alongside the track wire and carrier. In such an event, it is preferable to apply the second receptacle 35 in inverted or partly turned position in order to make the installation close and have it clear the given installation.

It is seen from the description of the receiving unit that not only is the clamp 40 adjustable on the supporting rod in a longitudinal or rotary direction, but after this has been done it is still possible to swing the receptacle 35 vertically or laterally by virtue of the universal joint of the cup 35b and bolt 38, whereby to adapt the bumper bar to the course of the track wire 33. Thus, the bumper bar is struck squarely, and a bearing for it is provided by means of the lodging of its spring within the receptacle and by means of the bearing of the bar in the receptacle end 35a. The action of the bumper bar is therefore direct and no lateral force is exerted thereon to cause it to deviate and affect any other parts. Further, the fact that the bumper 34 is square holds it and the catch in proper alinement and relation with the receptacle 35, eliminating tendencies for the mechanism to twist or vibrate.

I claim:

1. A cash carrier comprising a support, a sending unit for the cash receptacle extending therefrom, a bracing bar leading from the support, and sending unit elements depending from the bracing bar and perforated to fit the same, said bracing bar being of non-circular cross-section, and the form of said perforations being to correspond.

2. The structure of claim 1, the cross-section of said bar being angular and the form of said perforations being to correspond.

3. The structure of claim 1, the cross-section of said bar being square and the form of said perforations being to correspond.

4. A cash carrier comprising a sending station for the cash receptacle, a track wire extended from the sending station to lead the receptacle in the direction of a receiving station, a support at the latter, a bumper bar to stop the receptacle, a guide for the bumper bar, a universal joint connection between the guide and the support, and securing means embodied in said connection for retaining the angular adjustment of the guide to aline the bumper bar with the course of travel of the receptacle.

5. The structure of claim 4, said universal joint connection comprising a ball joint.

6. The structure of claim 4, the guide carrying anchoring means for the receiving end of the wire track.

7. A cash carrier comprising a sending station for the cash receptacle, a track wire extended from the sending station to lead the receptacle in the direction of a receiving station, a support at the latter, a clamp for the support and angularly adjustable relative to the latter, a bolt for the adjustment of the clamp and having a ball-shaped head, a washer between the latter and the clamp, said washer being cup-shaped to seat the head and the clamp being concaved to seat the washer, a bumper bar to stop the receptacle, and a guide for the bumper bar extended from said washer, the latter being slotted from the passage aperture for the bolt to constitute the connection between the clamp and the guide a ball joint.

8. The structure of claim 4, the bumper bar being of angular cross-section and the guide having a bore of corresponding form and size for the sliding of the bumper bar whereby to dispose the guide and bar against relative rotary motion.

9. A cash carrier comprising a sending station for the cash receptacle, a track wire extended from the sending station to lead the receptacle in the direction of a receiving station, a support at the latter, a clamp for the support and angularly adjustable relative to the latter, a bumper bar to stop the receptacle, a tubular guide receiving the bumper bar and with one end closed and bored for the slidable passage of the bumper bar, a shock-absorbing spring coiled about the latter in front of said closed guide end, a recoil spring mounted on the bumper bar behind said end, and a ball-joint connection between the guide and the clamp.

10. The structure of claim 9, the socket portion of said connection being an integral cup extension of said end of the guide.

11. The structure of claim 9, the walls of said guide comprising longitudinal skeleton bars joined at the ends of the guide.

12. The structure of claim 9, the opposite

end of the guide having a flange perforated for the passage of the track wire, and a hook carried by the guide for the anchoring of said wire.

13. The structure of claim 9, the opposite end of the guide having a marginal flange perforated at intervals in a rotary direction for the selective application and passage of the track wire, and hooks spaced in a rotary direction and carried by the guide for the selective anchoring of said wire, that hook being selected which is nearest to the perforation chosen to pass the wire.

14. A cash carrier comprising a vertical support, a bracing bar extended forwardly from the support, a wire track fixture pivotally secured to the support spacedly from the bracing bar and having an arm extending in a direction substantially at right angles to said bracing bar, said arm being adjustably secured longitudinally of said bracing bar, and a single track wire secured to that part of the fixture which is remote from the bracing bar.

15. A cash carrier comprising a vertical support, a bracing bar extended forwardly from the support and pivotally secured to the latter, a wire track fixture pivotally secured to the support spacedly from the bracing bar and having an arm spaced from the support and extending substantially at right angles to said bracing bar, said arm being adjustably secured longitudinally of said bracing bar to vary the angular relation between the support and the bracing bar, and a single track wire secured to the fixture at a point remote from the bracing bar.

In testimony whereof I affix my signature.

JAMES L. BALDWIN.
